UNITED STATES PATENT OFFICE.

WILLIAM GEORGE COWAN, OF VICTORIA, BRITISH COLUMBIA, CANADA.

CABINET FOR PAPER BAGS.

1,331,417.

Specification of Letters Patent. Patented Feb. 17, 1920.

Application filed August 9, 1919. Serial No. 316,433.

To all whom it may concern:

Be it known that I, WILLIAM G. COWAN, a citizen of Canada, residing at Victoria, in the Province of British Columbia and Dominion 5 of Canada, have invented new and useful Improvements in Cabinets for Paper Bags, of which the following is a specification.

This invention relates to store fixtures or furniture and has for its object the provision 10 of a cabinet adapted to hold all sizes of paper bags in properly graded sequence in such position that a bag may be removed with the utmost ease and simplicity without interfering with other bags, the device being 15 consequently sanitary and efficient in maintaining the bags in proper condition.

An important object is the provision of a cabinet of this character in which sliding follower members are disposed to the rear 20 of the various groups of bags whereby to urge the groups of bags toward the front of the cabinet from which they will be subsequently removed as needed, means being provided for engaging and holding these follower members at their rearmost positions at 25 the back wall of the cabinet whereby to facilitate filling of the various compartments with the bags.

Another object is the provision of a cabinet 30 of this character in which the various sizes of bags are selectively grouped and in which each and every size is instantly accessible, the device being also neat in appearance, and portable whereby it may be 35 moved to different desired locations within a store or the like.

An additional object is the provision of a cabinet of this character which will be simple and inexpensive in manufacture, highly 40 efficient and durable in use, labor saving, a good advertising medium, and altogether a general improvement in the art.

With the above and other objects and advantages in view the invention consists in 45 the details of construction to be hereinafter more fully described and claimed, and illustrated in the accompanying drawings, in which—

Figure 1 is a front elevation showing one 50 form of the cabinet,

Fig. 2 is a side elevation thereof with the side door swung into open position,

Fig. 3 is a longitudinal sectional view taken from front to back of the cabinet and showing the means for latching the follower 55 plates;

Fig. 4 is a detail view of one of the follower plates,

Fig. 5 is a front elevation of a modified form of the cabinet, showing the same general construction but a different arrangement of the bags,

Fig. 6 is a front elevation of a still further modified form of the device arranged for use as or beneath a counter, 65

Fig. 7 is a detail perspective view of the locking bar.

Referring more particularly to the drawings, the numeral 10 designates an upright casing, formed of wood, metal, or other 70 suitable material, having a suitable base 11. The top of the casing 10 is shown at 12 and is inclined. Disposed within the lower part of the casing is a shelf or false bottom 13 which is parallel with the top 12, and disposed 75 throughout the length of the casing are other similar shelves 14. One side of the casing is closed by a hinged door 15 and this door is provided with grooves 17 which accommodate strips 17^a adjacent the shelves 13 and 80 14. Any suitable means may be provided for holding the door 15 closed. The strips 17^a and the opposite side of the casing are provided with grooves 17^b, as shown.

These grooves coöperate with the shelves 85 13 and 14 to form compartments 18 which are of different sizes to accommodate bags of different sizes and the bags are arranged within these compartments in folded position and standing upon one side edge with 90 their bottom flaps extending toward the side having the door. The front of the casing is of course provided at the end of each compartment 18 with an opening 19 which is formed at one end to be of the same size as 95 the bottom flap of the associated size of bag and which is provided throughout a portion of its length with flanges 20 extending forwardly over the face of the outermost bag and serving as retaining means for preventing the bags from being removed from the compartments by any other than lengthwise movement in the direction of the door 15. 100

In order that the bags may be normally

urged toward the front of the cabinet, I provide within each of the compartments 18 a follower plate 21 provided at its upper corners with inclined projecting strips 21^a which are freely slideable and which hold the follower plates in upright position within the compartments. Each follower plate carries side cleats 22 between which extends a transverse rod or wire 23. Disposed 5 within the rear portion of the casing at substantially its center, is a vertical bar 24 provided at its upper end with a handle 25 projecting through the top 12 of the cabinet and normally urged upwardly by a curved 10 leaf spring 26 engaging the bottom of the cabinet and the lower end of the bar 24. This bar is provided with a recess 27 adjacent one shelf and serving to limit the movement of the bar, and the bar is also provided with slots 28 opening at their upper 15 ends onto the outer edge of the bar.

In order to fill the cabinet with bags it is first necessary that the door 15 be opened and the various follower plates 21 be pushed 20 upwardly as far as possible within the compartments 18, it being understood that at this time the bar 24 is depressed. The bar being depressed when the follower plates 21 are moved into engagement therewith, the 25 rods or wires 23 carried by the follower plates will enter the slots 28 at their upper ends, whereupon the operator releases pressure upon the handle 25 which results in upward movement of the bar 24 under the influence of the spring 26 so that the rods or 30 wires 23 will be engaged within the lower ends of the slots 28 and the follower plates be consequently held in position. The various compartments 18 are then filled with the 35 bags in the position above described, after which the door 15 is shut and the bar 24 moved downwardly to permit disengagement of the rod or wires 23 from the slots 28 therein. Owing to the inclination of the 40 various compartments, the weight of the bags, together with the weight of the follower plates, will cause the bags to be fed constantly toward the openings in the front of the cabinet and the bags will of course be 45 removed as needed, through these openings, as above described. When a compartment is empty the follower plate will close the opening and prevent unsightliness and the follower plate may carry attractive advertising 50 matter.

Referring to Fig. 5 it will be seen that the cabinet 30 is of the same general construction except that instead of having a base it is preferably provided with legs 31 carrying casters or rollers 32 whereby the device 55 may be easily portable. In this form the front of the cabinet is provided with a plurality of openings 33 identical with the openings 19 in the previously described form 60 except that they are more uniformly graded

in point of size. Furthermore, in this form of the device, extra compartments 34 are provided within which bags of progressively decreasing sizes are arranged in upright folded position. The operation is the same 70 as that of the preceding form.

Referring to Fig. 6, it will be seen that I have constructed a cabinet formed as a counter or formed for arrangement beneath a counter, either construction being optional. 75 In this form all the main compartments 35 arranged at the lower portion of the casing 36 are adapted to contain the bags in vertical position and the larger of these compartments have extending thereacross a rod 37 80 disposed within suitable slots 38 in the front wall of the cabinet between the compartments whereby to prevent outward sagging or bulging of the bags. Arranged above the main or lower compartments 35 are smaller 85 compartments 39 which are arranged to receive the bags disposed upon their side edges and these compartments 39 are accessible for purposes of filling by swinging open a hinged portion 40 of the cover of the cabinet. 90 In other respects, the construction and operation of this form is the same as that of the first described form.

While I have shown and described the preferred embodiments of my invention, it 95 is of course to be understood that I reserve the right to make such changes in the form, construction, and arrangement of parts as will not depart from the spirit of the invention or the scope of the subjoined claims. 100

Having thus described my invention, I claim:—

1. A device of the character described comprising a cabinet having its front provided with a plurality of openings and provided internally with a plurality of bag receiving compartments, said compartments registering with the opening in the front of the cabinet and extending upwardly toward the rear of the cabinet, a follower plate disposed in upright position within each compartment and engaging against the group of bags disposed therein, and means for holding all of said follower plates adjacent the back wall of the cabinet whereby to permit 115 refilling of the compartments, said means comprising a vertically movable bar engageable with said follower plate. 110

2. A device of the character described comprising a cabinet having its front provided with a plurality of openings and provided internally with a plurality of bag receiving compartments, said compartments registering with the openings in the front of the cabinet and extending upwardly toward 125 the rear of the cabinet, a follower plate disposed in upright position within each compartment and engaging against the group of bags disposed therein, and means for holding all of said follower plates adjacent the 130

back wall of the cabinet whereby to permit refilling of the compartments, said means comprising a vertically movable bar disposed adjacent the rear of the cabinet and provided at intervals with vertical slots leading at their upper ends to the forward edge of the bar, resilient means normally forcing said bar upwardly, and a transverse rod carried by each follower plate and engageable within one of said slots upon manipulation of said bar. 10

In testimony whereof I affix my signature.

WILLIAM GEORGE COWAN.
